UNITED STATES PATENT OFFICE.

SAMUEL P. RAFFEL, OF NEW YORK, N. Y.

DRESS, COAT, AND SUIT BOX, AND HANGER.

Application filed February 3, 1928. Serial No. 251,645.

This invention relates to certain new and useful improvements in a convertible dress, coat and suit box and hanger of that general character in which a box is so constructed 5 that while it serves as a means for storing or transportation of a dress or suit, or other article of wearing apparel, it may also serve as means for the suspension of the garment while in a closet, or wherever desired, and 10 which will prevent wrinkling of the dress or other article, while being carried in stock, or when carried home by the purchaser, and at the same time making a compact box which can be readily carried without danger of the 15 dress or other article therein being wrinkled or in danger of being crushed or otherwise damaged. The structure is such that the dress may be supported on the hanger whether the latter be disposed within the 20 confines of the box, or turned so that it may be entirely without the confines of the box.

The present invention has for its object, among others, to provide an improved box of this general character which will be capable 25 of manufacture at small cost, quickly foldable with the garment therein, and having novel closure means at the juncture of the fold line of the box, as well as for the line of juncture of the wall flap at the end of the box 30 and the end flap, which secures the said end flap tightly in position after the garment has been placed within the box.

Other objects and advantages of the invention will hereinafter appear, and the novel 35 features thereof will be particularly pointed out in the appended claims.

The invention, in its preferred form, is clearly illustrated in the accompanying drawings, which, with the numerals of reference marked thereon form a part of this 40 application, and in which

Figure 1 is a top plan view of the blank from which my improved box is formed.

Figure 2 is a view looking at the interior 45 of the box with the side flaps folded.

Figure 3 is a plan view of the box showing a dress therein, with two side flaps folded down upon the dress and the side flaps of the other section or half of the box turned inward 50 and the box ready to be folded and the locking of the same.

Figure 4 is a perspective view of the box in its closed and locked condition.

Figure 5 is a cross section on the line 5-5 55 of Figure 4, looking in the direction of the arrows.

Figure 6 is a cross section on the line 6-6 of Figure 4, looking in the direction of the arrows, the section being taken on a line at right angles to the section line of Figure 5. 60

Figure 7 is a perspective detail of a foldable closure fold.

Figure 8 is a plan view showing, on an enlarged scale, a modified form of such closure fold. 65

Like numerals of reference indicate like parts throughout the several views.

The material employed in the construction of the box may be of the well-known materials usable for such purposes; card-board, of suitable character, that can be bent without breaking and easily foldable to produce the desired flaps, etc., may be employed. 70

My improved box is what might be termed a "loop-hole dress box." 75

In carrying out my invention, I employ a single blank 1 of sheet material, such as card-board, paste-board, straw-board, or any equivalent thereof, and this is bent or folded, or creased, to enable ready folding so that the 80 parts thereof may be easily and quickly arranged in their proper positions relatively to each other and then to be extended and subsequently, if desired, folded with the minimum tendency to be broken in handling, so that the 85 box is designed for repeated use for any of the purposes to which it may be put.

The portions 2 and 3 are the receptacle members, between which are the transverse crease lines 4 and 5 upon which the top and 90 bottom portions are designed to be bent as the box is set up for use, the portions between these crease lines forming the wall member 6 as seen in Figure 4, where the box is shown as in its closed condition and locked at the 95 opposite end.

The member 3 is creased at its opposite edges as at 7 to provide for ready folding of the side flaps or walls 8, 8. The member 2 is creased upon opposite sides as seen at 9, 9, 100 leaving the flaps 10, 10, as clearly seen in Fig. 1.

At its outer end the member 3 is creased at 11 to permit easy folding of the hanger member 12, which latter is provided with openings 13, which latter provides for the ready insertion of the garment and also constitutes a hanger for the same and the box when desired. The outer end portion of this member 12 may be snipped off or inclined as seen at 110 14, while between the junction of the inner edge of this member 12, and the adjacent wall

of the member 2, portions 15 may be removed to facilitate bending of the member 12 without danger of breaking at the crease.

The opposite end of the blank, that is at 5 the outer end of the member 2, is creased as at 16 and 17, see Fig. 1, while the foldable wall 18 which extends outwardly beyond said creases, is formed at its ends with terminal locking tongues 19, 20. The member 18 at 10 each end is creased as at 21, see Fig. 1, upon which creased lines the member 18 is bent when the box is closed and in position to be locked.

The adjacent ends of the members 2 and 3, 15 between the portions 8 and 10, are creased at 22 and 23 and the rectangular portion 24 thus formed is provided with the diagonal crease 25, as shown clearly in Fig. 1, for a purpose soon to be described.

20 Likewise opposite ends of the portion 26 between the creases 16 and 17 at the locking tongue end of the blank, are creased as at 27 and 28 and also provided at this point with the diagonal crease 29, as clearly illustrated 25 in Fig. 1.

The member 2, near its opposite edges and adjacent its outer end is provided with slits 30, as shown in Fig. 1, for the reception of the terminal locking tongues 19 and 20 when the 30 box is closed and it is desired to lock the same.

In order to facilitate folding of the portions 23 and 24 between the members 2 and 3, I may sometimes slit one of the side walls of either portion 23 or 24, as shown at 27 in 35 Fig. 8. The function and operation are the same as though the slit 27 was not present but in using heavier material it is found to be advantageous.

In use, the dress or other garment is hung 40 upon the hanger member 12, being passed through the slot 13 and then laid flat in the box as indicated in Fig. 3. The side members 8 are then folded downwardly flat upon the adjacent portions of the garment or toward 45 each other, as seen in Fig. 3, and then the foldable members 10 are turned inwardly upon the outer crease line 9 and the portion between the crease lines being bent at right angles to the adjacent edges of the blank as 50 seen in Figs. 2 and 3.

The portions between the creases 9 constitute the side walls 31 of the box as seen in Fig. 3. The member 3 of the box is then turned upon the crease line 4, the portion 6 55 between these crease lines serving to form the side wall of the box as shown in Fig. 4, in which view the box is shown in its closed position and locked by the terminal locking tongues 19 and 20. As the member 2 is 60 folded downwardly toward the member 3, the closure portions 24 are automatically

bent inwardly along the creases 22, 23 and 25, to form a closure between the top and bottom portions of the closed box and the side walls thereof as will be readily understood upon reference to the different views. It is to be noted that in the folding of the box the garment is protected against creasing by means of the flaps 8, 8, and in such closing of the box the flaps 10 fold over the 70 adjacent faces of the portions 8, as will be readily understood upon reference to Fig. 5.

The member 18 is then folded upon the crease line 16, and again upon the crease line 17, so that the portion 18 extends over the 75 adjacent portion 2 of the box and then the locking tongues 19 and 20 engage over the edge of the box and the terminal portion of these tongues will engage upon the outer portion 2 and then be forced into the slits 30 80 upon the opposite face of the box, the creased members between the two creases 16 and 17 automatically folding inwardly to close the joint between the adjacent slots and thus serve to exclude the dirt or dust from the 85 interior of the box.

Modifications in detail may be resorted to without departing from the spirit of the invention or sacrificing any of its advantages.

What I claim is:—

1. In a convertible suit box and hanger comprising portions foldable toward each other with a hanger member at one end of one of said portions, and side portions foldable toward each other to prevent creasing 95 of a garment contained within the box, the other portion having flaps for cooperation with those of the first-named portion, there being on the opposite end of the box an extension member extended over the one portion and embracing the side portion and having terminal locking tongues cooperable with the other portion.

2. In a combined suit box and hanger comprising opposed portions foldable toward 105 each other, and side flaps foldable inwardly toward each other and one of said portions having creased portions at an end thereof adapted to fold inwardly as the box is closed, and serving to form dust-excluders, one of 110 said portions having locking elements embracing the edge and face of the other portion and cooperating with the latter.

3. In a convertible suit box and hanger comprising portions foldable toward each other, a closure embracing one face of the box and opposite edges thereof and having locking engagement with the opposite face of the box.

In testimony whereof I affix my signature.

SAMUEL P. RAFFEL.
